(57) **CLAIM**

The ornamental design for eyewear frames, as shown and described.

DESCRIPTION

FIG. 1 is a front perspective view of the eyewear frames of the present invention;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.

The broken lines illustrate portions of the eyewear frames and form no part of the claimed design.
